UNITED STATES PATENT OFFICE.

ORSON F. SKINNER, OF HASTINGS, MICHIGAN, ASSIGNOR OF ONE-HALF
TO FRANK W. COLLINS, OF HASTINGS, MICHIGAN.

SAFETY-BUNG ATTACHMENT.

No. 820,871.

Specification of Letters Patent.

Patented May 8, 1906.

Application filed March 2, 1905. Serial No. 248,090.

To all whom it may concern:

Be it known that I, ORSON F. SKINNER, a citizen of the United States, residing at Hastings, in the county of Barry and State of Michigan, have invented a new and useful Safety-Bung Attachment, of which the following is a specification.

This invention relates to improvements in bungs for drawing beer or other liquids under pressure from casks, kegs, and similar receptacles.

The object of the invention is to provide a simple, inexpensive, and efficient device of this character in which the usual removable cork or stopper for closing the reduced end of the bung is dispensed with, said bung being provided with a threaded perforated plug, the removal of which is effected by the insertion of the draft-tube.

A further object of the invention is to provide means whereby the plug may be withdrawn from the keg or cask upon the withdrawal of the draft-tube.

With these and other objects in view the invention consists in the construction and novel combination and arrangement of parts hereinafter fully described, illustrated in the accompanying drawings, and pointed out in the claim hereto appended, it being understood that various changes in form, proportions, and minor details of construction may be resorted to without departing from the principle or sacrificing any of the advantages of this invention.

In the accompanying drawings, forming a part of this specification, Figure 1 is a longitudinal sectional view of a safety-bung constructed in accordance with my invention. Fig. 2 is a similar view showing the draft-tube in position to remove the plug. Fig. 3 is a similar view showing the plug threaded on the end of the draft-tube and the latter disposed within the cask or keg.

Similar numerals of reference indicate corresponding parts in all the figures of the drawings.

The improved device may be used in connection with any of the preferred forms of bungs now in general use and by way of illustration is shown applied to a bung 5 of the ordinary construction having a reduced or tapering end 6, adapted to be driven into the bung-hole 7 of a barrel, keg, or other receptacle 8.

The tapering or reduced end of the bung is 55 interiorly threaded, as indicated at 9, for engagement with the corresponding threads 10 of a removable plug or stopper 11, the latter being provided with an enlarged head 12, the annular flange 13 of which is adapted to engage the threaded end of the bung, and thereby prevent the escape of liquid from the keg during transportation or shipment. The plug or stopper 11 is provided with a reduced threaded extension 14, adapted to engage the 65 terminal threads of a removable draft-tube 15, which passes through a packing or bushing 16 and is preferably provided with a cock or faucet 17.

Extending transversely of the plug 11 is a 70 slot or opening 18, which intersects a vertical opening 19, formed in the threaded extension and through which the beer or other liquid flows to the draft-tube when the several parts are in the position shown in Fig. 3 of the 75 drawings.

The threads on the plug and its extension are preferably inclined in the same direction, so that when the threaded end of the draft-tube engages the shoulder 20 a further movement or continued rotation of said tube will unscrew the plug and permit the latter to be lowered within the barrel or keg, in which position the liquid is free to pass through the openings 18 and 19 to the draft-tube, as before stated. When it is desired to remove the plug, it is simply necessary to withdraw the bung carrying the draft-tube, when the plug may be readily unscrewed from the latter and again placed in position on the threaded end of the bung to be used for a second tapping.

The threaded plug may be provided with as many openings as may be found necessary to permit the proper escape of the liquid, and, if desired, a washer or gasket may be interposed between the annular flange of said plug and the threaded end of the bung in order to insure a tight joint.

From the foregoing description it will be 100 seen that there is produced an extremely simple and efficient device admirably adapted for the attainment of the ends in view.

Having thus described the invention, what is claimed is—

In a device of the class described, a hollow bung adapted to be driven into a receptacle, a detachable perforated plug threaded in the

driving end of the bung and having its upper end provided with a reduced threaded extension defining an annular shoulder and its lower end formed with a laterally-extending flange for engagement with the adjacent end of the bung, and a draft-tube spaced from the interior walls of the bung and provided with terminal threads adapted to engage the threaded extension and annular shoulder for releasing the plug when the draft-tube is rotated, said plug being provided with a plurality of openings extending transversely of the plug at the laterally-extending flange and

having a longitudinal passage communicating with said openings and with the draft-tube to thereby permit the discharge of the contents of the receptacle through said draft-tube when the plug is released by rotating the latter.

In testimony that I claim the foregoing as my own I have hereto affixed my signature in the presence of two witnesses.

ORSON F. SKINNER.
